UNITED STATES PATENT OFFICE.

JOSEPH OPPMAN, OF CONNELLSVILLE, PENNSYLVANIA, ASSIGNOR OF ONE-HALF TO
PETER MIKALARIAS, OF CONNELLSVILLE, PENNSYLVANIA.

PASTING AND CUTTING MACHINE.

Application filed January 30, 1922. Serial No. 532,876.

To all whom it may concern:

Be it known that I, JOSEPH OPPMAN, a citizen of the United States, residing at Connellsville, in the county of Fayette and State of Pennsylvania, have invented certain new and useful Improvements in Pasting and Cutting Machines, of which the following is a specification.

This invention relates to apparatus for simultaneously applying paste to rolls of paper and severing the same into strips of uniform widths, and has for one of its objects to simplify and improve the construction and increase the efficiency and utility of devices of this character.

Another object of the invention is to provide a device of this character which may be adapted to rolls of paper of varying widths, and to apply paste uniformly to the whole web and sever the same into strips of varying widths.

Another object of the invention is to provide a device of this character having means whereby the flow of paste to the paper may be accurately controlled.

With these and other objects in view the invention consists in certain novel features of construction as hereinafter shown and described and then specifically pointed out in the claim, and in the drawings illustrative of the preferred embodiment of the invention:

Figure 1 is a plan view of the improved apparatus with the roll of paper in position.

Fig. 2 is a transverse section on the line 2—2 of Fig. 1.

Fig. 3 is a front elevation with the roll of paper removed.

Fig. 4 is a rear elevation with a part broken away.

Fig. 5 is a sectional detail illustrating the construction of the trough member of the apparatus.

Fig. 6 is an enlarged sectional detail of the cutting wheel holder.

Fig. 7 is an enlarged sectional detail illustrating the manner of supporting the drum for rotation.

Fig. 8 is an enlarged sectional detail of

the adjusting device for the paste flow control.

The improved apparatus is designed more particularly for applying paste to and serving wall paper into webs of uniform widths, but may be readily adapted to applying paste and serving webs of paper of any width and length.

The improved apparatus comprises a supporting structure including a bottom member 10 and end member 11, of relatively heavy material, preferably of wood. Supported between the end members 11 is a trough preferably of sheet metal 12, and having one side about in line with the center of the trough, as shown at 13, and the other side extending upwardly as shown at 14.

The portions 12, 15 and 14 are embedded at their ends in channels within the end members 11, as shown in Fig. 5, to insure paste tight joints between the parts.

Extending between the end members 11 is an L-shaped member 15, preferably of sheet metal, and coacting with the upwardly extending side 14 of the trough to form a tank or reservoir for paste.

The side wall 14 of the trough also forms one wall of the tank, the latter underlying a portion of the trough as indicated at 16. A plurality of orifices 17 are formed in the bottom of the trough and provide communication between the bottom of the trough and the adjacent portion of the tank, as shown in Fig. 2.

A stay member 18 is disposed beneath the trough to support the same.

The tank is provided with a detachable cover 19.

Mounted for rotation in the trough 12 is a drum comprising a cylindrical body 20 and closed ends, one of which is shown at 21 in Fig. 7, and disposed in the end members 11 are internally threaded sleeves, one of which is shown at 22, to receive threaded pins 23 which engage by their inner unthreaded ends in wear sleeves 24 in the heads 21 of the drum.

By this means the drum is mounted for rotation on the end members 11 and is therefore rotative in the trough. The

"barrel" or body 20 of the drum is concentric to the curved portion of the trough and only slightly smaller than the same, so that a thin film of the paste will flow 5 through the orifices 17 into this thin space and be spread uniformly over the barrel of the drum as the latter is rotated, as hereafter explained.

Bearing upon the curved lower part of the 10 wall of the trough which also forms the adjacent wall of the tank, is a correspondingly curved cut-off plate 25 whose lower portion serves to close the orifices 17 when in its lower position and to open the orifices when 15 in its higher position, and partially close the orifices when in intermediate position. By this means the flow of paste from the tank to the thin space between the trough and drum can be controlled by adjusting the 20 plate 25.

Means are provided for adjusting the position of the member 25, consisting in a stud 26 rotative in the wall 14 of the trough and tank and with an eccentric 27 at one end 25 within the tank and a squared portion 28 and a threaded portion 29 externally of the wall 14.

Engaging on the squared portion 28 is a milled set collar 30, and engaging the 30 threaded portion of the stud is a milled clamp nut 31.

Bearing around the eccentric 27 is a strap device 32, and extending from the strap is a rod 33 pivoted at 34 to the closure member 35 25.

When the clamp nut 31 is reversely rotated, the member 30 may be freely rotated to correspondingly rotate the stud 26 and its eccentric member 27 to control the position 40 of the cut off 25, and thus correspondingly control the flow of the paste through the orifices. After the eccentric 27 has been adjusted to the required position, the clamp nut 31 is rotated to compress the member 30 against the wall 14 and thus lock the stud 26 and the eccentric 27 in position.

Extending between the end members 11 is a guide roller 35 having journals like those employed for mounting the drum 20—21, 50 and including milled clamp members 36 like the members 23.

The roller 35 is preferably located above the center of the drum 20—21, as shown in Fig. 2.

55 Formed in the inner or confronting faces of the end members 11 are vertical guideways 37 to receive the journals 38 of a bearing roller 39.

Formed in the confronting faces of the 60 end members 11 are horizontal guideways 40 to receive the ends of a rod 41 designed to support a roll of paper indicated at 42. The rod is held from displacement by hooks 41' as shown.

The end of the web 43 of paper is passed 65 between the barrel 20 of the drum and the bearing roller 39 and thence between the barrel 20 of the drum and the guide roller 35 and thence drawn upwardly, the pulling upwardly of the web of paper causing 70 the drum to be rotated and carry a thin film of paste with it and apply it uniformly upon the paper as it is drawn over the drum and held in contact therewith by the gravity of 75 bearing roller 39.

By this means the requisite amount of 80 paste is uniformly and evenly applied to the paper as it is drawn upwardly, and the paper held in contact with the drum by the weight of the bearing roller 39 with sufficient tension to insure the proper action.

By adjusting the member 25, as before described, the amount of the paste which passes into the confined space between the trough 12 and drum 20 and thereby carried 85 up against the paper 43, can be accurately gaged.

Extending between the end members 11 is a rod 44, and slidably and rotatively engaging the rod is a holding member 45 having a split bearing 46 provided with a clamp bolt 47, to enable the member 45 to be clamped upon the rod in adjusted position.

The member 45 is formed with an upwardly opening recess 48, and pivoted at 49 in the recess is an arm 50 having a cutting wheel 51 pivoted in one end. Formed upon the member 45 is an arching support 52 to receive an adjusting screw 53, to control the 90 position of the member 45 and the cutting wheel carried thereby.

A compression spring 54 is disposed in the recesses 48, and yieldably supports the recess engaging end of the member 50.

The rod 44 will be so disposed that the cutting wheel 51 bears against the guide roller 35, and thus severs the paper 43 as the latter is drawn upwardly.

The severing member being adjustable 100 longitudinally of the rod 44, it will be obvious that any required width of paper may be severed, and by providing a plurality of the severing devices the paper may be severed in a corresponding number of strips of any required width, or varying widths.

The improved apparatus is simple in construction, can be inexpensively manufactured of any required size and of any suitable material, and operates effectually for the purpose described.

The preferred embodiment of the invention is disclosed in the drawings and set forth in the specification, but it will be understood that modifications within the scope 115 of the claimed invention may be made in the construction without departing from the principle of the invention or sacrificing any of its advantages.

Having thus described the invention what is claimed as new is:—

In an apparatus of the class described, a semi-cylindrical trough, a drum rotative in said trough, a tank for paste having orifices providing communication between the tank and trough, a closure for the orifices, a rotative stud having an eccentric portion, a

rod having a strap enclosing said eccentric portion, and pivoted to said closure, and means for locking said stud in adjusted position.

In testimony whereof, I affix my signature hereto.

JOSEPH OPPMAN.
